UNITED STATES PATENT OFFICE.

ANDREW A. KRAMER, OF KANSAS CITY, MISSOURI.

CAN-RACK.

1,351,253.

Specification of Letters Patent. Patented Aug. 31, 1920.

Application filed May 3, 1920. Serial No. 378,365.

To all whom it may concern:

Be it known that I, ANDREW A. KRAMER, a citizen of the United States, residing at Kansas City, in the county of Jackson and State of Missouri, have invented certain new and useful Improvements in Can-Racks; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to vehicle tank construction and particularly to a can rack structure adapted to be associated with a vehicle tank.

The object of the invention is to provide an improved construction of can rack whereby the cans may be easily introduced into the rack and as easily removed therefrom when the occasion demands. To this end the invention consists in certain parts 25 and combinations of parts, all of which will be specifically referred to hereinafter, reference being had to the accompanying drawings, in which—

Figure I is a perspective view of a tank 30 to which my invention is applied.

Fig. II is a sectional view through the side panel, showing the manner of fastening the same to close the side of the can rack, and

35 Fig. III is a similar view with the panel in its open position.

The tank 1 is provided with bolsters or cradles 2 in spaced relation along the bottom of the tank. Secured to the bolsters 40 are can rack supports 3 which are preferably fastened to the vertical flanges 4 of the bolsters 2, as clearly shown in Fig. III. The supports or brackets 3 may be angular in cross section and the top flanges 5 are adapted to support a board or floor 6 which carries the lateral straps 7 fastened to the normally vertical straps 8 by pintles 9, whereby hinges are provided. The up-standing straps 8 carry a panel 10 which may consist 45 of sheet metal and the edges of the panel 10 are bent to provide right angularly projecting flanges 11 to receive the split tubes 12 whereby a bead is provided about the panel 10.

55 The ends of the can rack are shown as consisting of panels 13, having about their

perimeters laterally projecting flanges 14 whereby pan-shaped devices are formed, the lower flange of which may be secured to the board or floor 6. The ends 13 are connected 60 to the panels 10 by chains 15, one end of each chain being fastened to an end of the panel and the other end to the panel 10. The chains are of such length that the panel 10, which constitutes a door or gate, may 65 only swing a determined distance away from the tank 1 but far enough to permit the easy removal of the cans from the rack.

The panel 10 may be held in a substantially vertical position to coöperate with the 70 ends 13 to provide a substantially rectangular can rack by fastening devices connected to the flanges 14 and adapted to engage complementary devices on the panel 10. For example, the panel 10 is provided with a 75 forked, upstanding projection 16 adapted to be engaged by the link 17 pivoted to the bracket 18 on the flange 14 of the panel 13 and the link is shown as provided with a threaded end 19 carrying a wing nut 20. 80

When it is desired to secure the panel 10 in a substantially vertical position to lock in the can racks, the panel or gate 10 will be swung up against the vertical flanges and panels 13 and the link 17 will be dropped 85 into the forked portion of the member 16 whereupon the nut 20 may be screwed tightly against the member 16 to hold the panel or gate in its locked position, it being understood that there are at least two of the 90 locking devices, one at each end of the can rack.

When it is desired to release the panel or gate so that it may assume the position shown in Fig. III, the nut will be loosened, 95 the link will be drawn up to the position shown in Fig. III and the panel or gate may swing outwardly to the limit permitted by the chain or flexible connection 15.

It will be seen from the foregoing that the 100 device may be readily applied to existing types of tanks and that it will admirably serve the purpose for which it is intended.

What I claim and desire to secure by Letters-Patent is:

1. In a vehicle tank construction, a tank, bolsters supporting said tank, can brackets carried by the bolsters, a floor board carried by the brackets, upstanding walls supported by the floor board, each wall comprising a 110 plate having right angularly projecting flanges and arranged crosswise of the board,

a side member extending substantially the length of the floor board and hingedly connected thereto, and means connecting the side member to the upstanding walls.

- 5 2. In a vehicle tank construction, a tank, bolsters supporting said tank, can brackets carried by the bolsters, a floor board carried by the brackets, upstanding walls supported by the floor board, each wall comprising a 10 plate having right angularly projecting flanges and arranged crosswise of the board, a side member extending substantially the length of the floor board and hingedly connected thereto, means connecting the side 15 member to the upstanding walls, said means

permitting limited swinging movement of the side member, and locking members carried by the upstanding walls and removably engaging the side member.

3. In a tank construction, can rack 20 brackets, a floor member connected to said brackets, vertical, transversely disposed, upstanding walls carried by the floor member and having laterally projecting peripheral flanges, a side member connected to the floor 25 member, and locking devices carried by the upper flanges of certain of the walls and engageable with parts on the side member.

In testimony whereof I affix my signature.
ANDREW A. KRAMER.
